H. C. Jenkins.

ATTORNEY.

UNITED STATES PATENT OFFICE.

JOHN KELLY, OF LULING, LOUISIANA.

VACUUM-PAN.

SPECIFICATION forming part of Letters Patent No. 278,150, dated May 22, 1883.

Application filed February 8, 1883. (No model.)

To all whom it may concern:

Be it known that I, JOHN KELLY, a resident of Luling, in the parish of St. Charles and State of Louisiana, have invented a certain new and useful Improvement in Vacuum-Pans; and I do hereby declare the following to be a full, clear, and correct description of the same, reference being had to the annexed drawings, making a part of this specification.

10 This invention is specially adapted for use in the art of sugar-making, and it consists in the combination of a vacuum-pan and condenser, and provides for the escape from the former of the acids contained in the condensation of the vapors or steam arising therein.

15 The nature of my invention will be readily understood by referring to the accompanying drawings, whereon Figure 1 is a side view, partly in section, of a vacuum-pan provided with my improvements. Fig. 2 is a top view of my condensing-section, and Fig. 3 a top view of the spray-plate thereof.

On the drawings, the letter A represents an ordinary vacuum-pan. Between this pan and its cover B, I introduce a section or ring, C, having flanges d d', corresponding with those of the pan and cover, so as to be bolted thereto. The lower part of this section is provided with an internal dome, E, having an opening in the top thereof, said opening surrounded by a rim or flange, as shown at f, for preventing the condensations from overflowing the same. Immediately above the base of the dome E the ring or condensing-section is provided with 25 two (more or less) overflow-pipes, as at G G'. In its upper portion the ring C is provided with lugs h for the support of a detachable perforated dome-shaped spray-plate, I, having

a solid-pointed center, k, the diameter of the base of which is somewhat greater than that 40 of the flanged opening f or of the inlet-pipe l, so that the water, which, in the practice of the invention, flows through the pipe l, may, by falling on the said pointed portion, be scattered and made to descend through the perforations 45 in the form of a shower, condensing the vapors or steam arising from the interior of the vacuum-pan, and causing the same to pass outward through the overflow-pipes. The condensing ring or section C is furthermore 50 provided with openings m, which, by means of suitable branch pipes, n, connect with an annular pipe, n', which in turn is furnished with a flanged pipe, p, through which the vacuum is created.

Having described my invention, what I claim as new, and desire to secure by Letters Patent, is—

1. The combination, in a vacuum-pan, of a condensing-section having upper and lower 60 dome-shaped plates, the former provided with perforations around a solid center, and the latter having a flanged opening in its center, substantially as and for the purpose set forth.

2. The condensing-section C, having an internal dome, E, provided with a central flanged opening, f, overflow-pipes d d', and spray-plate I, in combination with the vacuum-pan A, having a cover and inlet-pipe, substantially as and for the purpose specified.

In testimony whereof I hereunto sign my name.

JOHN KELLY.
